(57) **CLAIM**

The ornamental design for a camera lens grip, as shown and described.

DESCRIPTION

FIG. 1 is an exploded perspective view of a camera lens grip, showing my new design;

FIG. 2 is a perspective view thereof;

FIG. 3 is a front elevational view thereof;

FIG. 4 is a rear elevational view thereof;

FIG. 5 is a right-side elevational view thereof, the left-side elevational view being a mirror image thereof;

FIG. 6 is a top plan view of the camera lens grip with the two sections separated for the ease of understanding thereof;

FIG. 7 is a bottom plan view of the camera lens grip with the two sections separated for the ease of understanding thereof;

FIG. 8 is a cross-sectional view taken along lines 8-8 of FIG. 7; and,

FIG. 9 is a cross sectional view taken along lines 5-5 of FIG. 5.

The broken lines showing a camera in FIG. 1 and FIG. 2 depict environmental subject matter and forms no part of the claimed design. The remaining broken lines represent portions of the camera lens grip that form no part of the claimed design.
